UNITED STATES PATENT OFFICE.

EDWIN N. TUTTLE, OF FITCHBURG, ASSIGNOR OF ONE-THIRD TO ANNA M. TUTTLE, OF LYNN, MASSACHUSETTS.

ROTARY STOOL.

SPECIFICATION forming part of Letters Patent No. 244,691, dated July 19, 1881.

Application filed February 28, 1881. (No model.)

To all whom it may concern:

Be it known that I, EDWIN N. TUTTLE, of Fitchburg, in the county of Worcester and Commonwealth of Massachusetts, have invented certain new and useful Improvements in Rotary Stools; and I do hereby declare the following to be a full, clear, and exact description of the invention, reference being had to the accompanying drawings, which form a part of this specification.

The object of this invention is to produce, as an article of manufacture, an improved rotary stool, whether made with a pivot or screw, which shall be strong and durable, more simple in construction, lighter in weight, and less liable to break or require repair than when made in the usual way.

The invention consists in the construction and combination of a mechanism for holding the top ends of the stool-legs, and receiving the pivot and screw of the seat, as hereinafter fully described.

Figure 1 is a sectional elevation of a stool embodying my invention, and shows the combination in detail. Fig. 2 is a plan of the base, comprising the legs A and cross-rounds B, as arranged to receive the cap C. Fig. 3 is a detached view of the spider wedge or casting G. Fig. 4 is a plan of the same. Fig. 5 is a plan of the cap C. Fig. 6 is a section of the cap on line y y. Figs. 7 and 8 are sectional views of the cap C and the wedge G, showing modified means of combination.

Are the legs of the stool, which are connected together by rounds B in the usual manner. The middle parts of the legs A are nearly vertical, and their upper parts are curved inward and upward to bring them into position (see Fig. 1) to receive the cap or case C, hereinafter described. The cap or case C, Fig. 5, is a thin plate of metal, irregular in form, with as many scallops D as the stool has legs. Upon the edge of this plate is a downward and slightly outward projecting flange F, and in the center is a hole, E, through which the top end of the spider-shaped casting G, hereinafter described, is made to pass. The dimensions of this cap can be varied according to the amount of curvature in the top part of the legs A. I make it so that, measured on

either of the dotted lines x x, it is from two and a half to three inches, and I believe the best results are obtained with a cap of substantially these dimensions.

The spider-wedge G, Fig. 3, consists of a circular portion, H, a recessed portion, I, and projecting ears J. On the outside of the circular portion H is cut a thread to receive a nut, M, as hereinafter described. The bottom part or base, I, is provided with as many recesses K and as many projecting ears J as the stool has legs A. Each recess K is concaved longitudinally, and from the bottom to the top it inclines gradually inward. Extending longitudinally through the center of the casting or wedge G is a hole, L, inside of which a thread is cut upon the casting G to receive the screw attached to the stool-seat, as hereinafter described. The dimensions of the casting or spider-wedge G should be determined with reference to the size of the cap C and the diameter of the stool-legs A.

In carrying out the objects of my invention, the legs A are bent into shape and connected by cross-rounds B, the whole being glued together and the cap C placed over the top ends, as shown in Fig. 2. The wedge G is then held in one hand under the cap C and with its recesses K opposite to the legs A. It is then pushed upward till the top end thereof projects through the hole E. The flange-nut M is then screwed on and the wedge drawn upward, forcing the legs A outward into the sockets formed by the scallops D in the flange of the cap, (all as shown in Fig. 1,) and in this manner the legs A are securely wedged in between the cap C and wedge or casting G. The screw N of the seat O is now introduced into the hole L, as shown in Fig. 1. In case of a pivot attached to the seat O, the hole L extends into but not quite through the casting G.

I am aware that the nut M may be dispensed with and other means employed to draw the casting G upward to the cap C; and though I prefer to use the nut M, still in Fig. 7 of the accompanying drawings I have represented, in combination with the cap and casting G, two bolts, P P, which I have successfully used for said purpose. Another method still would be to make the casting G in two parts, one part

consisting of the recessed portion I and another consisting of the circular portion H. If, now, this portion H is passed downward through the hole E so that the flange R, which is cast upon one end thereof, rests upon the top of the cap C, and the bottom end thereof, provided with a thread, is screwed into a hole in the wedge or base portion I, the clamping effect is produced substantially as before described. Fig. 8 is a sectional view, showing this combination in detail.

Having thus described my invention, what I claim as new, and desire to secure by Letters Patent of the United States, is—

1. The combination, in a stool, of legs, the

spider-wedge G, the cap C, and means, substantially as set forth, for clamping such wedge and cap upon said legs, as and for the purposes set forth.

2. The combination, in a stool, of legs, the cap C, the circular portion H, provided with screw-thread and flange R, substantially as shown, the wedge-piece I, having recesses K and ears J, all combined to operate as and for the purposes set forth.

EDWIN N. TUTTLE.
